Proctor, Kennedy & Campbell

ATTORNEYS

UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

Application filed July 29, 1922. Serial No. 578,295.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 This invention relates to typographical machines, such as linotype machines of the general organization represented in U. S. Letters Patent to O. Mergenthaler No. 436,532, wherein circulating matrices are released by escapements from a magazine or magazines in the order in which their characters are to appear in print and then assembled in line, the composed line transferred to the face of a mold, the mold filled with 15 molten metal to form a slug or linotype against the matrices which produce the type characters thereon, and the matrices thereafter returned through a distributing mechanism to the magazine or magazines from 20 which they started.

In these machines, the magazines are usually mounted in such manner that they may be quickly removed and replaced by other magazines containing different matrix fonts. 25 Before removing a magazine, however, it is customary to lock the matrices therein; in fact, this is necessary when the escapements are separated from the magazine, as otherwise the matrices would be free to escape 30 therefrom. Hence, the commercial machines are equipped with devices which prevent the removal of the desired magazine until the matrices have first been locked therein. In some instances, as when the magazine is 35 lifted out of engagement with the escapements, the locking devices are arranged to prevent the premature raising of the magazine; while, in other instances, as when the escapements are lowered out of operative 40 relation to the magazine, the locking devices are arranged to prevent the movement of the escapements as distinguished from that of the magazine. In either case, the locking devices referred to are controlled and actuated 45 by matrix locking means, which in locking the matrices in the magazine release it for removal. There are two kinds of matrix locking means now in use, one being in the

form of a detachable bar which is inserted and removed endwise through the edge of 55 the magazine, and the other being in the form of a permanently attached bar mounted on the magazine so as to be movable instantly to active or inactive position.

In the use of either kind of matrix locking bar, it sometimes happens that, during the process of removal and replacement of a magazine, the locking bar is withdrawn to an inactive position while the escapements are out of operative relation to the magazine, thus allowing the matrices to escape 60 and causing considerable annoyance and delay. The present invention is intended to overcome the foregoing objection and provides an automatic safety device which 65 prevents the unlocking of the matrices except when the magazine and escapements are in proper operative relation to each other. In the embodiment illustrated, this safety device is shown in connection with a 70 matrix locking bar of the kind permanently attached to the magazine, as the objection referred to is more serious in the use of that kind of bar, owing to the fact that a slight 75 movement of the bar will effect the release 80 of all of the matrices in the magazine. In carrying the invention into effect, specifically, the magazine is provided with a spring-actuated catch which is moved into and out 85 of engagement with the matrix locking bar (when the latter is in active position) as the escapements are moved out of and into 90 operative relation to the magazine, respectively. In this way, any accidental or unintentional release of the matrices at an improper time is effectively guarded against.

In the accompanying drawings, the invention has been shown merely in preferred form and by way of example and as applied to the particular style of machine referred 95 to, but obviously many alterations and variations may be made therein and in its mode of application which will still be comprised within its spirit. Generally speaking, it is to be understood the invention is not limited 100 to any specific form or adaptation except in so far as such limitations are specified in the claims.

Referring to the drawings:

Fig. 1 is a top plan view of the lower portion of a magazine equipped with the pres-

ent invention, certain of the parts being slightly broken away to expose the interior construction;

Fig. 2 is a transverse section taken on the line 2—2 of Fig. 1; and

Fig. 3 is a side elevation, showing the magazine and escapements in separated condition and with the safety catch in action.

In the present embodiment, the magazine 10 A containing the matrices X is removably supported upon the base frame B, while the key-operated escapements C controlling the release of the matrices from the magazine are mounted in a bar or frame C², which 15 latter is pivotally connected to the base frame, as at C¹, so as to allow the escapements to be swung into and out of operative relation to the magazine to permit its removal and replacement. The escapements 20 are held in operative relation to the magazine by a pair of spring-actuated latches L pivotally connected to the upper ends of laterally swinging arms M on the escapement frame. Cooperating with one of the 25 swinging arms M is a locking plate N slideable backwardly and forwardly in guideways formed in the escapement frame and provided at its rear end with a stud or projection N¹ adapted to engage in a recess or 30 aperture formed in the forward face of the swinging arm. The locking plate N is formed in its upper side with an inclined slot to receive the inclined stem portion O of a Z-shaped block O¹ mounted to slide trans- 35 versely to the right and left in corresponding guideways of the escapement frame. Due to this interconnection of the parts, the movement of the block O¹ to the right or left imparts a forward or backward movement to the plate N and causes the locking stud N¹ to be engaged with or disengaged 40 from the arm M, according to the direction of movement. A spring P bearing at one end against a fixed portion of the escapement frame and at its opposite end against an upstanding nose Q on the block O¹ tends 45 constantly to hold the latter to the right and consequently the locking plate N rearward with its stud N¹ engaged with the recess in the swinging arm M. The disengagement of 50 the locking plate N from the swinging arm M is effected by a matrix locking bar, subsequently to be described, which is caused to engage the block O¹ and shift it to the left 55 against the action of the spring P. The foregoing parts are substantially the same as set forth in my prior Letters Patent No. 1,304,689, to which reference may be had if desired. This prior arrangement has been 60 selected merely by way of example and any other arrangement capable of functioning in the desired manner might be employed instead. In this connection, it may also be noted that only such parts as are immediately concerned with the present invention

have been herein illustrated, and it will be understood that the other parts of the machine may be as illustrated in the above patent or as embodied in any other class of machine, and this whether the machine is 70 equipped with a single magazine or a plurality of magazines.

The matrix locking device herein illustrated is of the specific form covered by my Patent No. 1,424,917 of August 8, 1922. As 75 fully set forth in that patent, said device is in the form of a transverse bar E permanently attached to the magazine and shiftable longitudinally in opposite directions, means being employed to project it sidewise 80 into the magazine when shifted to the left so as to lock the matrices against escape, and additional means being provided to withdraw it from the magazine when shifted to the right so as to permit the escape of the 85 matrices. The first-mentioned means consists of a plurality of buttons or protuberances A⁷ carried by the magazine A and adapted to cooperate with corresponding recesses or depressions E² formed in the upper 90 side of the bar, while the second mentioned means consists of a pair of headed pins E¹ extending upwardly from the bar and a pair of cam plates A⁴ secured to the magazine and formed with longitudinally arranged 95 slots A⁵ wherein the pins E¹ are slidably arranged. As these parts are fully described in the above mentioned patent, it seems unnecessary to discuss them in any further detail. However, it is pointed out that, when shifted to the left to active position, the matrix locking bar E imparts a corresponding movement to the block O¹ against the action of the spring P and consequently disengages the locking plate N from 100 the escapement supporting arm M, whereas, when shifted to the right to inactive position, the locking bar allows the block to be moved in the same direction by the spring to effect the reengagement of the locking plate with the supporting arm. In other words, the two locking devices are arranged and operated in such manner as to permit and prevent the removal of the magazine 105 as the matrices are locked and unlocked, respectively. It may be noted at this point that the matrix locking bar E is held in its leftmost or active position by means of a spring-actuated catch or dog F, which thus overcomes any tendency of the spring P to 110 move the bar from such position before the escapement frame is swung down. To release the matrices, it is merely necessary to depress the catch by hand, when the locking bar may be shifted to the right to inactive 115 position.

Turning now to the present invention, it sometimes happens, as before stated, that the matrix locking bar is accidentally or unintentionally shifted to the right at a time 120

- when the escapements are out of operative relation to the magazine, and this notwithstanding the fact that the catch F acts normally to hold the bar in its active position.
- 5 Thus, in interchanging magazines, the operator oftentimes prematurely disengages the catch F and pulls the bar E to the right before the escapement frame C² is swung back and locked in operative engagement
- 10 with the substitute magazine, even if the conditions are otherwise entirely favorable. In guarding against such occurrences, according to this invention, the magazine is provided with an automatic safety device
- 15 which prevents the unlocking of the matrices unless the escapements are in operative relation to the magazine. In the preferred embodiment illustrated, such safety device is in the form of a vertically swinging plate G pivoted at the rear to the magazine by a pin G¹ and formed at the front with a curved slot G² slidably engaged with a guide pin G³ on the magazine, see particularly Fig. 3. Between its ends, the plate G
- 20 is formed with a rectangular opening G⁴ to permit the passage therethrough of the matrix locking bar E, which latter is formed at its extreme left with a shoulder e adapted to stand just beyond the plate in the active
- 25 position of the bar. Normally, or when the escapements are in operative relation to the magazine, the plate G is held in an elevated position by the engagement of its projecting portion G⁵ with the escapement
- 30 frame C², which latter thus locates the upper wall of the opening G⁴ above or out of path of movement of the shoulder e (Fig. 2). When, however, the escapement frame is
- 35 swung downwardly (which is only permitted when the bar E occupies its leftmost or active position), the plate G will swing downwardly with it until arrested by the engagement of the upper wall of the opening G⁴ with the locking bar alongside of the
- 40 shoulder e, as shown in Fig. 3. The upper inner corner of the shoulder e is slightly bevelled to avoid any interference with the plate G. Gravity alone might be sufficient to enable the plate G to function in the
- 45 required manner, but it is preferred to employ a spring, such as the blade spring G⁶, to depress the plate and hold it in its depressed position. When thus depressed, the plate G presents a solid portion behind or
- 50 to the right of the shoulder e and consequently positively locks the bar E against movement toward the right. When, now, the escapements are swung back into operative relation to the magazine (which will
- 55 ordinarily be a substitute magazine), the plate G is elevated again by the escapement frame C² and clears the shoulder e, leaving the bar E free to be shifted to the right to inactive position when released by the manual disengagement of the catch F. Accord-
- ingly, the release of the matrices is permitted or prevented according to the position of the escapement frame, or more broadly speaking, according as the magazine and escapements occupy an operative or inoperative relation to each other.
- 70
- As previously stated, the foregoing improvements have been shown merely in preferred form and by way of example and as applied to a particular style of machine, but obviously many changes and adaptations will suggest themselves to those skilled in the art without departing from the scope of the invention.
- 75
- Having thus described my invention, its construction and mode of operation, what I claim is as follows:
- 80
1. In a typographical machine, the combination with a matrix magazine and a bank of escapements therefor, one of said parts being movable out of operative relation to the other, of means for locking the matrices in the magazine, and means actuated by the separating movement of the magazine and escapements for preventing the improper release of said matrix locking means.
- 85
2. In a typographical machine, the combination with a matrix magazine and a bank of escapements therefor, one of said parts being movable into and out of operative relation to the other, of means for locking the matrices in the magazine, and means actuated by the movement of the magazine and escapements into and out of operative relation to each other for permitting and preventing the release of said matrix locking means, respectively.
- 90
3. In a typographical machine, the combination with a matrix magazine and a bank of escapements therefor, one of said parts being movable out of operative relation to the other, of a locking device to hold said parts in operative relation, a second locking device to retain the matrices in the magazine and arranged to disengage the first mentioned locking device to permit the separation of the magazine and escapements, and an automatic safety device actuated by the separation of the magazine and escapements for preventing the improper release of the matrix locking device.
- 105
4. In a typographical machine, the combination with a matrix magazine and a bank of escapements therefor, one of said parts being movable into and out of operative relation to the other, of means for locking the matrices in the magazine, and automatic means carried by the magazine for permitting or preventing the release of the matrix locking means according as the magazine and escapements occupy an operative or inoperative relation to each other.
- 110
5. In a typographical machine, the combination with a matrix magazine and a bank of escapements therefor, one of said parts
- 120
- 125
- 130

being movable into and out of operative relation to another, of a locking device for holding said parts in operative relation, a second locking device to retain the matrices 5 in the magazine and arranged to cooperate with the first-mentioned locking device, and an automatic safety device carried by the magazine and acting to permit or prevent the release of the matrix locking device according as the magazine and escapements 10 occupy an operative or inoperative relation to each other.

6. In a typographical machine, the combination of a matrix magazine, a bank of 15 escapements movable at will out of operative relation thereto, means for locking the matrices in the magazine, and means carried by the magazine and actuated by the separating movement of the escapements for preventing the improper release of the matrix locking means.

7. In a typographical machine, the combination of a matrix magazine, a bank of 20 escapements movable into and out of operative relation thereto, means for locking the matrices in the magazine, and automatic means carried by the magazine for permitting and preventing the release of said matrix locking means as the escapements are 25 moved into and out of operative relation to the magazine, respectively.

8. In a typographical machine, the combination of a matrix magazine, a bank of 30 escapements movable into and out of operative relation thereto, a locking device for holding the escapement bank in operative relation to the magazine, a second locking device to retain the matrices in the magazine and arranged to cooperate with the first- 35 mentioned locking device, and an automatic safety device carried by the magazine and acting to permit or prevent the release of the matrix locking device according to the position of the escapement bank.

45. 9. In a typographical machine, the combination with a matrix magazine and a bank of escapements therefor, one of said parts being movable into and out of operative relation to the other, of a matrix locking bar 50 permanently attached to the magazine and shiftable to active or inactive position thereon, and an automatic safety device carried by the magazine and acting to permit or prevent the release of the matrix locking bar 55 according as the magazine and escapements occupy an operative or inoperative relation to each other.

10. In a typographical machine, the com-

bination with a matrix magazine and a bank of escapements therefor, one of said parts 60 being movable into and out of operative relation to the other, of a locking device to hold said parts in operative relation, a matrix locking bar permanently attached to the magazine and movable to active or inactive position thereon and arranged to cooperate with the first-mentioned locking device, and an automatic safety device carried by the magazine and acting to permit or prevent the release of the matrix locking bar 65 according as the magazine and escapements 70 occupy an operative or inoperative relation to each other.

11. In a typographical machine, the combination with a matrix magazine and a bank 75 of escapements therefor, one of said parts being movable into and out of operative relation to the other, of a longitudinally movable matrix locking bar carried by the magazine, and an automatic safety device also 80 carried by the magazine and cooperating with the locking bar to prevent the improper release of the matrices, the said safety device being controlled in its action by the separating movement of the magazine and escapements.

12. In a typographical machine, the combination of a matrix magazine, a bank of 85 escapements movable into and out of operative relation thereto, a pair of laterally 90 swinging arms for supporting the escapements in operative relation to the magazine, a locking device to hold one of the supporting arms in engagement with the magazine, a matrix locking bar carried by the magazine and arranged to cooperate with the first-mentioned locking device, and an automatic safety device also carried by the magazine and acting to prevent the improper release of the matrix locking bar.

13. The linotype magazine A provided with the matrix locking bar E, the catch F, and the safety device G, all operating substantially in the manner shown and described.

14. In a typographical machine, the combination of the magazine A, the pivoted escapement frame C², the matrix locking bar E carried by the magazine, and the safety device G also carried by the magazine and cooperating with the locking bar E under the control of the pivoted escapement frame C².

In testimony whereof, I have affixed my signature hereto.

DAVID S. KENNEDY.
